UNITED STATES PATENT OFFICE.

KARL WILHELM DAUMANN, OF HAMBURG, GERMANY.

CATHODE ARRANGEMENT FOR X-RAY TUBES.

Application filed January 15, 1924, Serial No. 686,299, and in Germany January 11, 1923.

My invention relates to X-ray tubes and particularly to the cathodes of such tubes, and has for its object to provide a filamentary cathode for such tubes which will be particularly suitable for the purpose of diagnosis. When X-ray tubes are used for such a purpose it is desirable to have a focus of very small dimensions, that is to say, as nearly as possible a focal point, so that the X-rays may produce sharp images. Of course the use of a focal point places a great strain on the anticathode; in order to avoid or reduce this strain, it has been proposed to employ a focal band or strip, in such a manner as to give it the effect of a point by a sort of foreshortening. In practice, however, it has been found rather difficult to obtain a focal strip of sufficient sharpness by means of the cathode, and this difficulty has been particularly great in the case of X-ray tubes employing filamentary heated cathodes.

The invention relates to a novel construction of a cathode of the above indicated character. By my novel construction of the cathode and by the novel relative arrangement of the heated filament and of a collector associated therewith, I have secured very superior results which fully answer all the requirements, as has been proved by elaborate experiments.

According to my present invention the heated cathode consists of an elongated heated wire or filament located at or near the apex of two surfaces of the collector which converge toward a line parallel to the longitudinal axis of the cathode, or coincident with such axis. Preferably this elongated heated cathode has the shape of a closely wound coiled spring which fits into a slit at the apex of said collector surfaces, filling said slit almost entirely, there being left an amount of play just sufficient for the insertion or removal of such filament. These two converging surfaces of the collector, which extend lengthwise of the axis of the filament, are preferably used in conjunction with transverse surfaces at the ends of the collector and of the cathode, to prevent the escape of electrons lengthwise of the cathode.

A typical and satisfactory embodiment of this invention is illustrated by the accompanying drawings in which Fig. 1 is a longitudinal section through a portion of an X-ray tube embodying my invention; Fig. 2 is a longitudinal section taken in a plane

at right angles to Fig. 1 and Fig. 3 is a face view of the collector, the cathode, and associated parts.

In the embodiment illustrated, the elongated heated cathode 1 has the shape of a closely wound coil very much like a coiled spring, this coil being connected with, and carried by, the ends of wires 2 and 3 which serve for supplying current in any well known or approved manner for the purpose of heating the cathode. The latter is situated within an opening or slit 4, located between the adjacent longitudinal edges of the two converging surfaces 5 and 6 of the collector. The line in which said surfaces if continued would intersect, is parallel to the longitudinal axis of the cathode 1, or may coincide therewith; that is to say, the cathode 1 is located at or near the apex of the surfaces 5 and 6. As shown, the cathode fills the opening or slit 4 almost entirely, leaving only sufficient play for the convenient insertion and removal of the cathode. At both ends of the cathode 1, there are placed transverse surfaces 7 and 8 extending from one of the converging surfaces 5 and 6 to the other, and preferably these end surfaces 7 and 8 also converge toward the cathode. The line in which the surfaces 7 and 8 if continued would intersect, is transverse to the longitudinal axis of the cathode 1. The purpose of these end surfaces 7 and 8 of the collector is to prevent the escape of electrons from the ends of the longitudinal trough formed by the converging surfaces 5 and 6. The four surfaces 5, 6, 7, 8 thus form a unit in the shape of a hip-roof or of a box open at the wide end, and having at the narrow end a slit in which the cathode is situated. This box-like collector is supported by means of a trough-like body 11, the bottom of which also constitutes a screen to prevent the escape or scattering of electrons from the cathode in a direction away from the collector (that is to say, downwardly in Figs. 1 and 2). This support 11 is made of metal and is preferably connected with the collector to form a unit carried by supporting wires 9 and 10 suitably attached to the body of the X-ray tube. The wires 2 and 3 which supply the current to the cathode 1, pass through insulating tubes 12 and 13, made of glass or other suitable material and extending through the trough 11.

The arrangement of cathode and collector

described above is very efficient in producing a focal strip or band of X-rays which, when utilized in a direction oblique with reference to the axis of the filament, will have the effect of a focal point so that images of great sharpness will be produced.

The filament 1 is adapted to be heated to incandescence by the electric current supplied through the wires 2 and 3. The 10 screening body or trough 11, together with the collector walls 5, 6, 7, 8, compels the electrons to escape in one direction only, that is, through the open end of the collector, which open end faces away from the 15 screening body 11.

Various modifications may be made without departing from the spirit of my invention as set forth in the appended claims.

I claim:

- 20 1. A cathode arrangement for X-ray tubes, comprising an elongated filament having connections for passing an electric current therethrough and adapted to be heated to incandescence by such current and a collector elongated in the same direction as said filament and having converging surfaces at or near the apex of which said filament is located, said surfaces converging toward a line which is parallel to the longitudinal axis of the filament or coincides with such axis.
- 25 2. A cathode arrangement for X-ray tubes, comprising an elongated filament having connections for passing an electrical current therethrough and adapted to be heated to incandescence by such current, and a collector elongated in the same direction as said filament and having converging surfaces spaced adjacent to their apex to form an opening in which said filament is located, 30 said surfaces converging toward a line which is parallel to the longitudinal axis of the filament or coincides with such axis.
- 35 3. A cathode arrangement for X-ray tubes, comprising an elongated filament having connections for passing an electric current therethrough and adapted to be heated to incandescence by such current, and a collector comprising two surfaces which converge toward a line which is parallel to the longitudinal axis of the filament, 35 and also comprising two surfaces located at the ends of the first mentioned surfaces and converging toward a line which is transverse to the longitudinal axis of the filament.

ment being coiled about its longitudinal axis, and a collector elongated in the same direction as said filament and having surfaces 50 converging toward a line which is parallel or coincident with the said filament axis.

4. A cathode arrangement for X-ray tubes, comprising an elongated filament having connections for passing an electrical current therethrough and adapted to be heated to incandescence by such current, and a collector elongated in the same direction as said filament and having converging surfaces spaced adjacent to their apex to form an 55 elongated opening in which said filament is located, said surfaces converging toward a line which is parallel to the longitudinal axis of the filament or coincides with such axis, the said filament forming a coil which 60 fills said opening almost entirely.

5. A cathode arrangement for X-ray tubes, comprising an elongated filament having connections for supplying an electric current thereto and adapted to be heated to 70 incandescence by such current, a screening body located on one side of said filament, and a collector elongated in the same direction as said filament and located adjacent to the filament and open on that side of the 75 filament which is opposite to the one on which the screening body is arranged.

6. A cathode arrangement for X-ray tubes, comprising an elongated filament having connections for supplying an 80 electric current thereto, and adapted to be heated to incandescence by such current, and a collector comprising two surfaces which converge toward a line which is parallel to the longitudinal axis of the filament, 85 and also comprising two surfaces located at the ends of the first mentioned surfaces and converging toward a line which is transverse to the longitudinal axis of the filament.

In testimony whereof I have signed this specification.

KARL WILHELM DAUMANN.
